UNITED STATES PATENT OFFICE

131,493

DESIGN FOR A COMBINED MEMORANDUM PAD HOLDER, ASH TRAY, AND SUPPLY RECEPTACLE

Doak Norwood, Chicago, Ill.

Application August 5, 1941, Serial No. 102,695

Term of patent 14 years

To all whom it may concern:

Be it known that I, Doak Norwood, a citizen of the United States, residing at Chicago, in the county of Cook and State of Illinois, have invented a new, original, and ornamental Design for a Combined Memorandum Pad Holder, Ash Tray, and Supply Receptacle, of which the following is a specification, reference being had to the accompanying drawing, forming a part thereof.

In the drawing:

Figure 1 is a perspective view of a combined

memorandum pad holder, ash tray, and supply receptacle, showing my new design.

Figure 2 is a side perspective view thereof with the receptacle cover raised to show the supply receptacle.

Figure 3 is a front elevational view of the same.

I claim:

The ornamental design for a combined memorandum pad holder, ash tray, and supply receptacle, substantially as shown.

DOAK NORWOOD.
